UNITED STATES PATENT OFFICE.

JOHN H. OLSON, OF RED WING, MINNESOTA.

HAIR-BOBBING GAUGE.

Application filed May 6, 1924. Serial No. 711,415.

To all whom it may concern:

Be it known that JOHN H. OLSON, a citizen of the United States, residing at Red Wing, in the county of Goodhue and State 5 of Minnesota, has invented certain new and useful Improvements in Hair-Bobbing Gauges, of which the following is a specification.

This invention relates to new and useful 10 improvements in hair-bobbing gauges.

The primary object of my invention is to provide a gauge of this character which acts as a guide for the shears or other instruments employed and thus greatly facilitates 15 and renders more accurate the operation of bobbing the hair.

A further object of my invention is to provide a gauge of the character specified 20 which may be easily and readily fitted to any head.

A still further object of my invention is to provide a hair-bobbing gauge which may be adjusted to regulate the cutting of the 25 hair to any desired length and in which the bottom band may be adjusted circumferentially or vertically or tilted at an inclination to facilitate the operation of cutting the hair longer in the back as desired by many people who curl their hair.

A still further object of my invention is to provide a device of the character specified which is simple and economical in construction and highly efficient in operation.

With the foregoing and other objects in view that will appear as the nature of my invention is better understood, the same consists in the novel features of construction, combination and arrangement of parts illustrated in the drawings and more particularly 35 pointed out in the appended claims.

In the accompanying drawings which are for illustrative purposes only and are therefore not drawn to scale,

Figure 1 is a side elevation, illustrating 45 the application of my invention.

Figure 2 is a back view.

Figure 3 is a plan view.

Figure 4 is a view similar to Figure 1, 50 the bottom band tilted down or lowered to facilitate the cutting of the hair longer in the back.

Referring to the drawings for a more particular description of my invention, and in which drawings like parts are designated by like reference characters throughout the several views, A designates the bottom band

and B and C the upright, side and back supporting straps, respectively. The bottom band A is made in two corresponding sections 1 and 2, whose back overlapping ends 3 are provided with longitudinal registering slots 4 to receive the shank 5 of the adjusting screw 6. The shank of this screw also extends through a corresponding transverse opening 7 in the lower end of the upright back supporting strap C for threaded engagement with a wing nut 8 which is tightened up to hold the overlapping ends of the bottom band sections in adjusted position. A washer 9 may also be employed 70 between the head 10 of the screw 6 and the inner face of section 2 of the bottom band, the purpose of which will be apparent. The bottom sections 1 and 2 are pivotally connected intermediate their ends but nearer their front ends, as at 11 to the lower ends of the side supporting straps B which permits the bottom band to be tilted down to facilitate the operation of cutting the hair longer at the back as desired by many people who curl their hair.

The upper overlapping ends 12 of the side supporting bands are formed with longitudinally disposed registering slots 13 and may be held in adjusted position by the screw and wing nut 14 and 15, respectively. The shank of screw 14 also extends through a longitudinal slot 16 formed in the upper front end of the back supporting strap C and the cuts works against the outer face of said strap. Hence, when the nut 15 is tightened up, the upper end of the back strap as well as the upper overlapping ends of the side straps are held in adjusted position. A washer 17 may be employed between the head 18 of the screw 14 and the inner face of one of the side supporting straps if desired.

The side and back supporting straps as well as the bottom band are preferably 100 formed of thin, flat, resilient metal strips and owing to this fact and the adjustable connections illustrated and described, the device may be easily and readily fitted to any head preparatory to the hair-bobbing operation; also the bottom band may be raised or lowered to regulate the length of the hair or the bottom band tilted down to facilitate the operation of cutting the hair longer at the back than at the front, as illustrated in Figure 4 of the drawings.

In practice the lower edge of the bottom

band acts as a guide to the barber in cutting the hair evenly.

The upper edges of the overlapping back ends of the bottom band are graduated as at 19; also the front edges of the upper overlapping ends of the side supporting straps graduated as at 20 and one edge of the upper end of the back supporting strap graduated as at 21 to facilitate the even adjustment of the device in fitting the same to the head preparatory to the hair-bobbing operation.

From the foregoing description taken in connection with the drawings, it is thought that the construction, operation and advantages of my invention will be readily understood without requiring a more extended explanation.

Having described my invention what I

claim as new and desire to secure by Letters Patent, is:

1. A hair bobbing gauge comprising a bottom band, side and back supporting straps for said bottom band and means for adjusting the latter vertically or circumferentially or tilting the same either up or down in a vertical plane.

2. A device of the character specified comprising upright, side and back supporting straps, a bottom band pivoted at opposite sides to the lower ends of the side supporting straps and suitable connections for adjusting bottom band circumferentially, vertically, or at an inclination with a horizontal plane.

In testimony whereof he affixes his signature.

JOHN H. OLSON.
